JAMES I. PECK, OF DEANSVILLE, NEW YORK.

Letters Patent No. 98,998, dated January 18, 1870.

IMPROVED TONGUE AND THILL-COUPLING.

The Schedule referred to in these Letters Patent and making part of the same.

To all whom it may concern:

Be it known that I, JAMES I. PECK, of Deansville, in the county of Oneida, and State of New York, have invented a new and useful Improvement in Tongue and Thill-Coupling; and I do hereby declare that the following is a full, clear, and exact description thereof, which will enable others skilled in the art to make and use the same, reference being had to the accompanying drawings, forming part of this specification.

The object of my invention is to provide a thill-coupling which shall not only be easily and quickly detachable, as well as simple, strong, and cheap, but whose main feature shall be the construction, whereby a double bearing-surface is formed, thereby insuring much greater safety of connection and durability of parts than has heretofore been the case.

In the accompanying drawing—

Figure 1 is a perspective top view of a coupling, constructed according to my invention.

Figure 2 is an end view of the same.

Similar letters of reference indicate corresponding parts.

This thill-coupling is formed of two parts, A and B. The part A (or the "clip") is rigidly attached to the axle of the buggy, and is a plate of metal, with its outer end coiled to something like a half circle, forming a hook for receiving the draught. There is a vertical slot through the hook, which extends back to receive the thill-iron B.

C represents a T, through the foot D of the thill-iron, which T fits into the hook in the clip A. The foot D of the thill-iron fits the slot in the clip, and its end forms an arc of a circle, E, the centre of which circle is the centre of the T, C.

The part B and the part D of the thill-iron are both flat, and the planes of their flat surfaces stand at a right angle with each other.

The breadth of the foot D (or the length of the arc E) is sufficient to allow of any required vertical motion in the thills, and still keep the T in its place in the hook. To detach the thills, it is only necessary to raise them, so that the arc E will leave the slot, when the foot can be readily lifted up through the slot. For attaching the thills, they are raised in the same manner, and, when they are brought down, and the circle E enters the slot, the T finds its place in the hook, and the coupling is complete.

Thus it will be perceived, by slotting the plate A at its outer end, and curving the forks, thus formed, around the pivot-bolt C, a double bearing or connection is formed, whereby, if one part of the fork or bolt should be broken, or in any way injured, the other will remain intact, and the coupling still perform its function. Furthermore, it is evident that the coupling will last double the time of those having but a single bearing-surface.

Having thus described my invention,

I claim as new, and desire to secure by Letters Patent—

The part A of the coupling, slotted longitudinally at its outer end, to receive the foot D of the thill-iron B, and having its fork ends curved partially around the ends of the pivot-bolt C, whereby a double bearing-surface is formed, as and for the purpose specified.

JAMES I. PECK.
